(57) **CLAIM**

The ornamental design for a water heater fitting as shown and described.

DESCRIPTION

FIG. 1 is a perspective view, taken from a front, left side of a first embodiment of a water heater fitting;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view, taken from a front, left side of a second embodiment of a water heater fitting;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a perspective view, taken from a front, left side of a third embodiment of a water heater fitting;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top plan view thereof;

FIG. 21 is a bottom plan view thereof;

FIG. 22 is a perspective view, taken from a front, left side of a fourth embodiment of a water heater fitting;

FIG. 23 is a front elevation view thereof;

FIG. 24 is a rear elevation view thereof;

FIG. 25 is a right side elevation view thereof;

FIG. 26 is a left side elevation view thereof;

FIG. 27 is a top plan view thereof; and,

FIG. 28 is a bottom plan view thereof.

The broken lines depict portions of the water heater fitting that form no part of the claimed design. FIGS. 15 to 19 and 22 to 26 include symbolic breaks along the length. The area between the break lines forms no part of the claimed design.

1 Claim, 28 Drawing Sheets
